ent now consists of a lifting head, a vertical thrust rod, and a frame. The frame is a central vertical tube with a plurality of spacer elements secured thereto. The lifting head is secured to the frame and is vertically movable thereon between an upper position and a lower position. The lifting head is so located with respect to the frame as to be engaged by the latter and to be moved thereby into locking relation with the thrust rod when the lifting head is raised to its upper position. In consequence,

COIL-HANDLING APPARATUS

George E. Bronson, Naugatuck, Conn., assignor to
The American Brass Company, a corporation
of Connecticut

Application August 31, 1949, Serial No. 113,457

8 Claims. (Cl. 294—67)

1 This invention relates to apparatus for handling coiled materials. It provides an improved form of apparatus that can be lowered through the center of a stack of coils and that may then be actuated to pick up the stack, or on which a stack of coils can be built, in either case for the purpose of conveniently lifting and transporting the stack as a unit.

Many different articles of commerce are handled during manufacturing operations, and for shipping and storage purposes, in the form of coils. Metallic rods and wires, rope of various types, and both metallic and non-metallic tubing, are examples of materials commonly handled in the form of coils. Single coils often are conveniently handled manually or by conventional crane hooks, but for many purposes it is desirable to handle stacks of coils as a unit. The present invention provides a sturdy and easily operated apparatus for doing so, and which may be used equally well for handling stacks of coils either in the open or in closely confined quarters.

The apparatus of the invention comprises a frame adapted to serve as a supporting core for a stack of coils and which may be lowered through such a stack for the purpose of picking it up and supporting it in stack form. A plurality of feet are pivotally connected to the bottom of the coil frame. These feet are movable about such pivotal connection between a lateral position wherein they project beyond the core frame for supporting the bottom of a stack of coils and a vertical position wherein they are retracted from such coil-supporting position and may be inserted into or withdrawn through the center opening of the stack of coils. A thrust rod which is vertically movable with respect to the frame between upper and lower limits is pivotally connected at its lower end to said feet. Thereby movement of the thrust rod to its upper limit causes the feet to be moved to their vertical retracted position, and movement of the thrust rod to its lower limit swings the feet to their lateral coil-supporting position.

One or more latches are pivotally secured to the frame near its upper end in position to interlock with the thrust rod when the latter is at its lower limit. Beneath the latches is a lifting head which is secured to the frame and is vertically movable thereon between an upper position and a lower position. The latches are so located with respect to the lifting head as to be engaged by the latter and to be moved thereby into locking relation with the thrust rod when the lifting head is raised to its upper position. In consequence,

when the apparatus is raised by the lifting head, the latter is brought to its upper position and thereby the latches are moved into engagement with the thrust rod, locking it at its lower limit, so that the feet are held in their lateral coil-supporting position. Separate lifting means are attached directly to the upper end of the thrust rod, and when the apparatus is carried by such separate lifting means (in which case the lifting head is held by its own weight at its lower position and the latches consequently are not in locking engagement with the thrust rod), the thrust rod is raised to its upper limit and the feet are moved to their vertical retracted position.

2 A preferred embodiment of lifting apparatus according to the invention is shown in the accompanying drawing, wherein:

Fig. 1 is a cutaway perspective showing the new apparatus as used for handling a stack of coils in the close confines of a narrow tank;

Fig. 2 is an elevation partially in section showing the coil-handling apparatus of Fig. 1 in the position in which its feet are laterally extended for supporting a stack of coils;

Fig. 3 is a view similar to Fig. 2, but showing the apparatus in the position in which its feet are in their retracted vertical position;

Fig. 4 is a cross section, taken substantially along the line 4—4 of Fig. 2; and

Fig. 5 is a view of the lower end of coil-handling apparatus having feet of somewhat different form than is shown in Figs. 1 to 3.

The apparatus shown in the drawings comprises a central vertical tube 10 which constitutes a main frame element. Attached to the tube 10 are upper and lower spiders 11 and 12, to which in turn a plurality of spacer elements 13 are secured by pins 13a. The central tube, the spiders, and the spacer elements together form a frame structure adapted to serve as a supporting core for a stack of coils. The distance from the outside edge of any spacer 13 to the outside edge of the spacer diametrically opposite is only a little less than the diameter of the center openings of the coils to be handled, so that when the coils are stacked around the spacers, the stack of coils is held upright thereby.

A thrust rod 14 is positioned axially within the tube 10 and is movable with respect thereto in an axial direction. The thrust rod is of somewhat greater length than the tube, and projects from it at both ends.

A plurality of feet 15 are provided at the bottom of the apparatus. The feet are members having more or less the form of a shallow inverted U

(as seen in Fig. 2), and their inner legs 16 are attached by pivot pins 17 to a spider 18 rigidly fastened to the lower end of the thrust rod 14. The inner legs 16 of the feet are also provided with slots 19 through which pivot pins 20 extend. The pins 20 are secured to downwardly extending projections of the spider 12, whereby the feet are attached by pin-and-slot pivotal connection to the main frame of the apparatus.

By virtue of the pivotal connection of the feet both to the thrust rod and to the projections 21 of the frame spider 12, the feet may be moved back and forth between a lateral position for supporting the bottom of a stack of coils surrounding the spacers 13 (as shown in Fig. 2) and a vertical retracted position in which they may be inserted into or withdrawn through the center opening of a stack of coils (as shown in Fig. 3). Movement of the feet from the lateral to the vertical retracted position is effected by axial movement of the thrust rod 14 upwardly with respect to the frame of the apparatus. The slots 19 lie at an angle of about 45° to the coil-supporting edge surface of the feet, sloping downwardly and inwardly when the feet are in their lateral coil-supporting position and sloping downwardly and outwardly when the feet are in their retracted vertical position, and they are of such length as to permit the amount of sliding movement of the feet relative to the pins 20 that is necessary to permit movement of the feet between the lateral and vertical positions.

It is evident that if the thrust rod is firmly locked at its lowest limit of travel with respect to the tubular frame member 20, the feet 15 will be securely held in their lateral coil-supporting position (i. e. the position shown in Fig. 2) whether or not the apparatus is resting on a floor. Locking of the thrust rod at its lower limit of travel is accomplished in the apparatus shown in the drawings by the provision of a pair (or more) of latches 22 fastened by pivot pins 23 to a boss 24 rigidly connected to the upper end of the tubular frame member 10. The latches 22 are provided with latch hooks 25 above the 45 boss 24, and with downwardly extending projections 26 below the boss. The downwardly extending projections are of sufficient weight so as normally to swing the latch hooks 25 laterally outwardly to the position shown in Fig. 3. The latches may, however, be rocked on their pivot pins 23 so as to cause the latch hooks 25 to engage with the upper surface of a latch plate 27 secured to the upper end of the thrust rod 14 (which position of the latches is shown in Fig. 2).

The apparatus is provided with a lifting head 28, more or less in the shape of a mushroom head, which is slidably mounted on the tubular frame member 10 between a lower position where it rests against a collar 29 firmly attached to the tubular member 10 and an upper position in which it is in engagement with the boss 24. The upper portion of the lifting head 28 is formed with an annular cam surface 30, and the lower projections 26 of the latches 22 are formed with corresponding cam surfaces 31. As the lifting head 28 is raised to its upper position, the cam surfaces 30 and 31 come into engagement and the latch hooks 25 are forced inwardly into position for interlocking with the latch plate 27, thereby to lock the thrust rod 14 at its lower limit of travel and to hold the feet 15 in their lateral coil-supporting position. When the lifting head 28 is not raised, it is held by its own 75

weight at its lower position in contact with the collar 29, thereby enabling the latches to be swung away, by the weight of their lower projection 26, from interlocking engagement with the latch plate 27 on the thrust rod.

The undersurface of the lifting head 28 is formed with an annular groove 32 in which prongs 33 of lifting tongs 34 may engage. When the apparatus, with its feet 15 in the lateral position shown in Figs. 1 and 2, is lifted from the floor by engaging the tongs 34 with the lifting head and then raising it, the lifting head is first brought to its upper position in which it forces the latches 22 into interlocking engagement with the latch plate 27 at the upper end of the thrust rod. Thereafter, with continued lifting by the tongs 34, the entire apparatus is raised from the floor with the feet 15 still held in their lateral coil-supporting position, and consequently any stack of coils positioned about the spacers 13 and resting on the feet 15 is lifted and may be transported as a unit by the crane or other apparatus from which the tongs 34 are suspended.

In order to withdraw the apparatus from a stack of coils, a lifting cap 35 is attached to the thrust rod 14 just above the latch plate 27. The lifting cap 35, like the lifting head 28, is similar in shape to a mushroom head, and is provided with an annular groove 35a in its undersurface so that it may be engaged by the lifting tongs 34. So long as the lifting head 28 is not held in its raised position by the lifting tongs or other means, it is held by its own weight at its lower position in which the latches 22 are released from interlocking engagement with the latch plate 27. Consequently if the apparatus is lifted by engaging the tongs 34 with the lifting cap 35 and then raising it, the thrust rod is first drawn upwardly through the tubular member 10 to its upper limit of travel. Thereby the feet 15 are brought to their vertical retracted positions, and by continuing lifting of the apparatus in this manner, it may be withdrawn through the center of the stack of coils.

So long as the apparatus remains suspended by engagement of the lifting cap 35 with the crane hook or other lifting device, it remains with its feet in their retracted vertical positions. When the apparatus is again lowered to the floor, it is necessary that the feet once again assume their lateral coil-supporting position. For this purpose, the outer legs 36 of the feet are provided with smoothly rounded projections 37. These projections are so located and shaped that when the feet are in the vertical retracted position, the outer edge surfaces 38 of the outer legs 36 slope inwardly and upwardly. When the apparatus with its legs in their vertical positions is lowered to the floor, it is these projections which first make contact with the floor, as shown in Fig. 3. Then as the weight of the apparatus is released by the crane or other lifting device, it is at first transmitted to the feet 60 through the pivot pins 17, causing the feet to swing outwardly about the pins 20 to their lateral coil-supporting positions. The smoothly rounded projections 37, and the upward and inward slope of the edges 38 of the outer legs 65 of the feet, facilitate sliding of the feet along the floor as this motion takes place. Finally, the apparatus comes to rest with the feet in the position shown in Fig. 2.

In the form of apparatus shown in Fig. 5, the feet 15 are provided with modified outer legs

designed to carry freely rotatable caster wheels 40. The wheels 40 take the place of the smoothly rounded projections 37 shown in Fig. 2 and facilitate outward movement of the feet from the vertical retracted position to the lateral coil-supporting position when the apparatus is lowered to the floor.

An advantage of the new apparatus is the ease with which it permits introducing a stack of coils into the close confines of a pickling barrel 41 or other tank, and withdrawing it therefrom, as illustrated schematically in Fig. 1. It is a laborious and difficult job to load the coils manually into such a vessel, and a more difficult one still to thus remove them therefrom, but with the new apparatus loading and unloading of the barrel is very easily accomplished. The bottom of the barrel is provided with a series of blocks 42 spaced apart circumferentially so as to permit the feet 15 of the apparatus to extend between them. When a stack 43 of coils is lowered by the apparatus into the barrel 41, the bottom of the stack comes to rest on the blocks 42, and thereafter the apparatus may be lifted by the cap 35 to withdraw it through the center of the stack. To remove the stack from the barrel, the apparatus is lowered, while suspended by the cap 35, through the center of the stack, and when it comes to rest on the bottom of the barrel, the feet assume their lateral positions in the manner previously described. Thereafter, the entire stack may be withdrawn from the barrel by lifting the apparatus by means of the lifting head 32.

In addition to its advantage for handling stacks of coils in the close confines of pickling barrels and the like, the new apparatus has many advantageous uses in handling coiled materials wherever such materials are manufactured, processed, or stored.

I claim:

1. Apparatus for handling coiled materials comprising a frame adapted to serve as a supporting core for a stack of coils, a plurality of feet pivotally connected to the coil frame at the bottom thereof, said feet being movable about their pivotal connections to the frame between a lateral position wherein they project beyond the frame for supporting the bottom of a stack of coils and a vertical position wherein they are retracted from such coil-supporting position, a thrust rod vertically movable with respect to the frame between upper and lower limits and pivotally connected at its lower end to said feet, whereby movement of the thrust rod to its upper limit moves the feet to their vertical retracted position and movement of the thrust rod to its lower limit moves the feet to their lateral coil-supporting position, a lifting head secured to the frame and movable vertically thereon between an upper position and a lower position, latches pivotally secured to said frame in position to interlock with the thrust rod when the latter is at its lower limit, thereby to lock the thrust rod at its lower limit, said latches being positioned to be engaged by the lifting head and to be moved thereby into locking relation with the thrust rod when the lifting head is raised to its upper position, and lifting means attached directly to the upper end of the thrust rod for raising it to its upper limit and for carrying the apparatus, whereby when the apparatus is carried by the lifting head the latter is raised to its upper position and the latches are moved into engagement with the thrust rod

for locking it at its lower limit, thereby holding the feet in their lateral position, and when the apparatus is carried by the lifting means attached to the thrust rod the latter is held at its upper limit, thereby holding the feet in their vertical retracted position.

2. In coil-handling apparatus of the character described, a frame, feet pivotally secured to the frame and movable through an arc between a vertical retracted position and a lateral coil-supporting position, a vertically movable thrust rod pivotally secured to said feet, said rod being movable between an upper limit in which it holds the feet in their vertical retracted position and a lower limit in which it holds the feet in their lateral coil-supporting position, latches pivotally secured to the frame in position to interlock with the thrust rod when the latter is at its lower limit to hold the feet in their lateral coil-supporting position, a lifting head movable on the frame and normally spaced below the latches but movable upwardly into engagement therewith, whereby when the apparatus is lifted by said lifting head the latches are moved into interlocking engagement with the thrust rod and the feet thereby are held in their lateral coil-supporting position, and separate lifting means secured directly to the thrust rod, whereby when the apparatus is lifted by such separate means the thrust rod is raised to its upper limit and the feet are moved thereby to their vertical retracted position.

3. Apparatus according to claim 2, characterized in that the lifting head is slidable vertically on the frame and is formed with a hook-receiving annular recess in its lower surface and with a latch-engaging cam face on its upper surface, said lifting head being held normally by its own weight sufficiently below the latches to be out of contact therewith, and further characterized in that the latches are provided with cam surfaces corresponding to the cam face of the lifting head, whereby lifting of the head causes the cam face thereof to engage with the cam surfaces of the latches and move the latches into position for interlocking with the thrust rod.

4. Coil-handling apparatus of the character described comprising a central frame member, an axial thrust rod movable vertically with respect thereto, a plurality of feet each of which is pivotally connected at its inner end to the thrust rod and each of which is pivotally attached by pin-and-slot connection to the frame at a position substantially radially outwardly from the pivotal connection to the thrust rod, whereby when the thrust rod is moved downwardly with respect to the frame the feet are moved pivotally to a substantially lateral coil-supporting position, and when the thrust rod is moved upwardly with respect to the frame the feet are moved pivotally to a vertical retracted position.

5. Apparatus according to claim 4, characterized in that each foot is a shallow inverted U-shaped member the inner leg of which is pivotally connected to the thrust rod and the outer leg of which provides support for the foot when the apparatus is resting on a floor with the feet in their lateral coil-supporting positions.

6. Apparatus according to claim 5, characterized in that the slot of the pin-and-slot connection between each foot and the frame is formed in the inner leg of the foot and slopes downwardly and outwardly when the foot is in its vertical retracted position and slopes downwardly and inwardly when the foot is in its lateral coil-

supporting position, whereby the weight of the apparatus when it is resting on a floor with the feet in the vertical retracted position tends to force the feet to the lateral coil-supporting position.

7. Apparatus according to claim 6, characterized in that the outer edge surface of the outer leg of each foot slopes inwardly and upwardly when such foot is in the vertical retracted position, thereby to facilitate movement of the foot to the lateral coil-supporting position under the influence of the weight of the apparatus when it rests on a floor with the feet in the vertical retracted position.

8. Coil-handling apparatus of the character described comprising a central frame member, a thrust rod movable vertically with respect thereto, a plurality of feet each of which is pivotally connected at its inner end to the thrust rod and each of which is pivotally connected to the frame at a position substantially radially outwardly from the pivotal connection to the thrust

rod, whereby when the thrust rod is moved downwardly with respect to the frame the feet are moved pivotally to a substantially lateral coil-supporting position, and when the thrust rod is moved upwardly with respect to the frame the feet are moved pivotally to a vertical retracted position, and a roller attached to the outer end of each foot, whereby when the apparatus rests on a floor with its feet in the vertical retracted position movement of the feet along the floor to their lateral coil-supporting positions is facilitated.
